ATTY.

UNITED STATES PATENT OFFICE.

ALBERT JACOBSON, OF NEOPIT, WISCONSIN.

DESIGN FOR A PICTURE-FRAME.

44,312.

Specification for Design.

Patented July 8, 1913.

Application filed April 26, 1913. Serial No. 763,909. Term of patent 8½ years.

To all whom it may concern:

Be it known that I, ALBERT JACOBSON, a citizen of the United States, residing at Neopit, in the county of Shawano and State of Wisconsin, have invented a new, original, and ornamental Design for Picture-Frames, of which the following is a specification, reference being had to the accompanying drawing, forming part thereof.

The figure is a front elevation of a picture frame, showing my new design.

I claim:

The ornamental design for a picture frame, as shown.

ALBERT JACOBSON.

Witnesses:

H. C. D. ASHFORD,
BERNARD C. NELSON.
